Primary Examiner — Selina Sikder(74) *Attorney, Agent, or Firm* — Maier & Maier, PLLC(57) **CLAIM**

The ornamental design for a lamp control switch, as shown and described.

DESCRIPTION

FIG. 1 is a front elevational view of a first embodiment of a lamp control switch, showing our design;
 FIG. 2 is a rear elevational view thereof;
 FIG. 3 is a right side elevational view thereof;
 FIG. 4 is a left side elevational view thereof;
 FIG. 5 is a top view thereof;
 FIG. 6 is a bottom view thereof;
 FIG. 7 is a perspective view thereof; and,
 FIG. 8 is a perspective view of another embodiment thereof. The broken lines throughout the figures show portions of the lamp control switch that form no part of the claimed design.

1 Claim, 8 Drawing Sheets(56)
